DESIGN FOR A TOY ALPHABET PICTURE REGISTER OR SIMILAR ARTICLE

Daniel C. Cahalane, Hillsdale, N. J., assignor to The Hoge Manufacturing Company, Inc., a corporation of New York

Application May 14, 1937, Serial No. 69,359

Term of patent 7 years

To all whom it may concern:

Be it known that Daniel C. Cahalane, a citizen of the United States and resident of Hillsdale, in the county of Bergen and State of New Jersey, has invented a new, original, and ornamental Design for a Toy Alphabet Picture Register or Similar Article, of which the following is a specification, reference being had to the accompanying drawing forming part thereof, in which the figure is a perspective view of a toy alphabet picture register, showing my new design as it appears with two of the letter keys depressed.

The back and the right hand side of the article are plain similar to the side shown.

I claim:

The ornamental design for a toy alphabet picture register or similar article, as shown and described.

DANIEL C. CAHALANE.
